UNITED STATES PATENT OFFICE.

CARL AUER, OF FRAGARIA, WASHINGTON, ASSIGNOR OF ONE-FOURTH TO FRANK RUETH, OF WASHINGTON, DISTRICT OF COLUMBIA.

CLOCK REWINDING DEVICE.

1,194,928.

Specification of Letters Patent. Patented Aug. 15, 1916.

Application filed December 14, 1915. Serial No. 66,745.

To all whom it may concern:

Be it known that I, CARL AUER, a citizen of the United States, and a resident of Fragaria, in the county of Kitsap and State of Washington, have invented a new and Improved Clock Rewinding Device, of which the following is a full, clear, and exact description.

This invention relates to winding devices 10 for clocks and particularly to an automatic rewinding device for various kinds of clocks, as for instance, power or master clocks, and has for an object the provision of an improved arrangement whereby the motor for 15 moving the power weight of the clock is arranged on said power weight and forms part of same.

Another object in view is to provide a motor or power member on the weight of a 20 clock together with associated mechanism, whereby the weight will be caused to climb the chain or cable connected with the clock for operating the same, said climbing action restoring the weight to its wound position.

A still further object in view is to provide a power means for a traveling weight which acts as the weight of a clock, the arrangement being such that when the weight is in 30 its highest position the power will be turned off and when in its lowest position the power will be turned on, so that the weight is raised by the actuation of power means and is allowed to move downwardly by the action 35 of gravity, the downward movement of the weight causing the usual movement of the power chain for rotating the clock.

In the accompanying drawings:—Figure 1 is a front view of a rewinding structure 40 embodying the invention; Fig. 2 is an enlarged fragmentary front view of the weight and associated parts shown in Fig. 1; Fig. 3 is a section through Fig. 2 on line 3—3; Fig. 4 is a detail fragmentary sectional view through Fig. 2 on line 4—4; Fig. 5 is a front elevation of the switch and switch 45 shifting mechanism embodying certain features of the invention, the casing being shown in section; Fig. 6 is a section through Fig. 5 on line 6—6; Fig. 7 is a view of the switch shifting mechanism on the opposite side to that shown in Fig. 5; Fig. 8 is a detail fragmentary sectional view through Fig. 5 on line 8—8; Fig. 9 is a view similar to 55 Fig. 5 except the parts have been set for

shifting the switch when the weight of the clock has reached its highest point; Fig. 10 is a view of the opposite side of the mechanism shown in Fig. 9.

In constructing a device embodying the invention means have been provided which will not affect the construction of the clock and which forms parts of the weight operating the clock. The construction is an addition to the weight now commonly used 65 in master clocks and other similar clocks and is mounted principally on the weight so as to form part of the weight though certain connecting parts are provided so that electrical current may be supplied to the motor 70 for operating the moving parts. In clocks run by weights, as for instance, master clocks and the like, a power or driving chain is used for rotating the parts of the clock-work and a weight is mounted so as to move 75 the chain. The weight just referred to, by the present invention, acts in the usual way of moving a weight under the action of gravity but as soon as the weight reaches its lowermost position the motor and associated 80 parts are immediately started so that the weight of the clock will automatically be raised by the climbing action of the weight, the same acting on the chain so that there will be a continual tension on the chain not 85 only during the downward movement of the weight but during the rewinding thereof.

Referring to the accompanying drawings by numerals, 1 indicates the usual frame for a clock, which clock is provided with a power pulley 2 and a master shaft 3. Passing over the power pulley 2 is a power chain 4 which is operated by a weight 5 but which is of the endless variety and passes over a pulley 6 at the bottom of the frame 95 7. The frame 7 is provided with a base 8 and uprights 9 and 10, said uprights being connected with what may be termed a top 11 on which the clock framework 1 is mounted. This framework provides a space 100 or compartment in which the weight 5 may move up and down. Connected with the framework 7 are uprights 12 and 13 which are provided with insulating strips 14 and 15 carrying metallic conductors 16 and 17. 105 The conductor 16 is connected through wire 18 to a battery 19 while the opposite side of battery 19 is connected to conductor 17 by a wire 20. It is of course evident that the battery 19 could be grounded on the frame 7 110

on one side while the opposite side could be connected to conductor 16, though preferably a completely insulated circuit is desirable. The pulley 6 over which the lower end of the chain 4 passes is mounted upon a lever 21 pivotally mounted at 22 on the upright 13. A set screw 23 is arranged so as to force the lever 21 downwardly and thereby act as a takeup for the slackness in the chain.

10 All of the moving parts are on the weight 5 including the motor which is supplied with current from battery or source of supply 19. Arranged on the upright 13 are stops 24 and 25 adjacent the lower and upper 15 ends respectively and a stop or abutment 26 intermediate the ends. These stops are adapted to engage certain mechanism mounted on the weight 5 hereinafter fully described, so that the current for motor 27 on weight 5 will be switched off when the weight has been moved to its highest position and will be switched on to the motor when the weight has reached its lowest position. The stop 26 actuates certain mechanism hereinafter described for setting the operating mechanism in proper position for actuation when either stop 24 or stop 25 is reached.

As shown in Figs. 5, 6 and 7 the operating parts are arranged at one side of the weight 5 and in a casing or housing 28. Fig. 5 shows one side of a part of the weight with part of the operating mechanism, while Fig. 7 shows the opposite side. A switch 29 is provided formed with segments 30 and 31, said segment 30 being connected to one of the bolts of motor 27 while segment 31 is connected with a contact shoe 32 engaging the conductor 17. A pivotally mounted arm 40 33 is arranged on plate 30 and carries a friction member 34 adapted to pass over the air gap 35. When the parts are in the position shown in Fig. 5 current is flowing from conductor 17 to shoe 32 and from thence to plate 31 over arm 33, plate 30, wire 36 and the motor 27, and after passing through the motor the current passes through wire 37 to the conductor 16.

It will be observed that arm 33 is provided with a rearwardly extending lever 38 so as to engage a projection 39 of the pivotally mounted arm 40. Arm 40 is pivotally mounted upon a sliding plate 41 held in place on the weight 5 by suitable pins 42 and 43 extending through slots 44 and 45. The plate 41 is cut away at 46 so as to allow a free pivotal movement of arm 40, said pivotal movement being caused by a guiding member 47 having the ends turned in opposite directions so that when the parts move from the position shown in Fig. 5 downwardly the pin 48 extending from arm 40 will strike the guide 47 and be moved to the right in said figure until the plate 41 has reached its extreme lower position and

has allowed the catch 49 to snap into notch 50. The pin 48 operates in a hollowed-out portion 51 in the weight 5 and guide 47 is also arranged in this hollowed-out portion and connected to the weight 5 in any suitable manner. The guide is bent at the lower end in such direction as to cause the pin 48 to move to the left as the plate 41 moves upwardly, while the pin 48 will move to the right when plate 41 moves downwardly. By this construction and arrangement the downward movement of plate 41 and arm 40 will not affect the lever 38 as the lug or extension 39 is moved away from said lever. However, when the plate 41 moves upwardly the extension 39 will strike the lever 38, which is in the dotted position shown in Fig. 9 and move the lever and associated parts to the full line position shown in Fig. 5.

The plate 41 is urged by spring 52 in an upward direction by reason of the fact that the spring surrounds a guiding pin 53 and presses against a lug 54 upstanding from plate 41 and against a stop 55 rigidly secured to the weight 5. The stop 55 forms part of a supporting and guiding plate 56 which supports and guides the plate 41, as shown more particularly in Fig. 6. The catch 49 which snaps into notch 50 of plate 41 continually presses against the edge of plate 41 by reason of the action of spring 57. The catch 49 forms part of a bell crank lever 58 which has an extension or projection 59 adapted to strike the stop 24 at the lower end of the frame 7 whereby plate 41 is released and is caused to move upwardly quickly by spring 52 and thereby turn the switch 29 to the position shown in Fig. 5.

When the weight 5 is moving upwardly the pin 60 (Fig. 5) strikes the stop 26 and as the weight continues to move upwardly the pin 60 together with the bell shaped lever 61 will be pulled or moved downwardly. The lever 61 is pivotally mounted upon a bracket 62 which is slidably mounted upon a guide rod 63 held in place by suitable brackets mounted in the casing 28. A rod 64 is also connected with sleeve or bracket 62 so that the lever 61 and rod 64 will remain stationary as the weight and associated parts move upwardly. Rod 64 is pivotally mounted to a double lever 65 which in turn is pivotally mounted at 66 on weight 5 in aperture 67. The double lever 65 is provided with an arm connected with rod 64 and with a second arm connected with spring 68, said spring being also connected with a pin 69 whereby the double lever is normally held in the position shown in Fig. 6. However, as the weight 5 moves upwardly the lever will be gradually turned and as it begins to turn the section 70 of arm 65 will strike pin 71 rigidly secured to plate 41 and will gradually move plate 41 downwardly against the action of spring 130

52. This movement continues until catch 49 has snapped into notch 50. As soon as this has been accomplished the cam edge 72 on the lever 61 strikes the cam member 73 so as to cause the pin or lug 60 to be disengaged from stop 26. The weight 5 continues to move upwardly until it reaches its extreme upper position, whereupon certain parts will be operated, hereinafter fully described. As the lever 65 is turned not only will section 70 move pin 71 downwardly but the opposite section, namely, section 74, will engage pin 75 rigidly connected with a sliding plate 76 and will move said sliding plate upwardly against the action of spring 78 which is mounted and arranged in a similar manner to spring 52 except to cause the plate 76 to move downwardly instead of upwardly. The movement of plate 76 is continued until the catch 49' has engaged the notch 50', which will take place simultaneously with the engagement of catch 49 with notch 50.

It will be observed that both the sliding plates 41 and 76 will move simultaneously and, consequently, will be locked in their upper and lower positions, respectively, simultaneously with or slightly before the lug or pin 60 is disengaged from stop 26. 30 The size of the notches 50 and 50' is such as to allow a slight movement so as to insure the engagement of the catches before the pin or lug 60 is released. Upon the releasing of pin or lug 60 the lever 65 will be released and will return to the position shown in Fig. 6 under the action of spring 68. When the lever 65 is moving under the action of rod 64 the plate 76 will be moving upwardly and as it moves upwardly the arm 40 carrying the projection 80 is swung away from the arm 81 by the guide 82 which is constructed similar to guide 49 shown in Fig. 5. The arm 79 is provided with a pin 83 which directly engages the guide 82 and which operates in a recess similar to recess 51, while the arm 79 operates in the cutaway portion 84. The guide 82 is bent at the upper end so that when the slide 76 moves downwardly pin 83 will be moved to the right in Fig. 7 so that the lug or projection 80 will strike the arm 83 and move the shaft 85 and as said shaft is rigidly connected with the switch arm 33 the switch will be moved to an open position, as shown in dotted lines in Fig. 9. However, as the sliding plate 76 moves upwardly the catch 49' engages notch 50' and locks or holds plate 76 in its raised position until the pin 86 extending from lever 87 carrying catch 49' strikes the stop 25 and is moved thereby as the weight 5 moves upwardly. This will cause the catch 49' to be disengaged and allow spring 78 to quickly force slide 76 downwardly to the position shown in Fig. 7, said downward movement causing the

movement of arm 81 and associated parts as above described. When this has been accomplished the upward movement of the weight 5 will be stopped as the current from battery 19 will be switched off. The weight 5 then acts in the usual capacity of a weight and gradually moves down under the action of gravity, such movement causing a movement of the chain 4, which movement is communicated to the clockworks through the master shaft 3.

The chain and associated parts may be made of such length as to cause the clock to run for any desired time upon one downward movement of the weight. However, as soon as the weight 5 reaches near the bottom of the framework 7 the pin 59 on lever 58 strikes stop 24 which will cause the catch 49 to move out of notch 50 and thereby release the slide 51 which will be moved upwardly quickly by spring 52 until the parts assume the position shown in Fig. 5. As the slide 41 moves upwardly pin 48 and guide 47 swing arm 40 to the right (Fig. 5) and cause the projection 39 to strike the extension 38, whereupon the switch arm 33 is moved to its closed position, as shown in Fig. 5, and current is again turned on to motor 27. This will cause the motor to operate without affecting the direction of movement of the chain 4 as the weight continues to act on the chain, though the weight is caused to climb the chain by mechanism hereinafter fully described. These up and down movements are continued as soon as the current is supplied by any suitable source. It will be observed that the current is supplied only while the motor is traveling upwardly and preferably such upward movement is comparatively fast while the downward movement of the weight is regulated by the particular make of clock and other considerations.

In order that the motor 27 may cause the weight 5 to climb the chain 4 the chain is looped over sheaves or pulleys 87 and 88, which sheaves or pulleys if desired may be made in the form of sprocket wheels so that the spurs or teeth of the sprocket wheels may engage the chain and cause a more positive action. Pulley 2 may also be made in the form of a sprocket wheel if desired. The pulley or sprocket wheel 88 is rigidly connected with a shaft 89 mounted in suitable bearings on a bracket 90. A worm gear 91 is also rigidly secured to shaft 89, said worm gear meshing with a worm 92 which worm is rigidly connected with a gear wheel 93 meshing with a pinion 94. The pinion 94 is connected to a shaft 95 of the armature of motor 27, whereby whenever motor 27 is operated the power will be transmitted through the various gears and worms just described to the sheave or sprocket wheel 88 and thereby cause the weight 5 to climb

upwardly. When the weight has been moved to its extreme upward position and the switch 29 has been opened the weight will naturally rest on the chain but sheave 88 cannot rotate by reason of the worm 92. This will cause the weight to be locked to one of the sections of the chain, namely, the section 4', as said section is looped over the sprockets 87 and 88. By arranging the rewinding mechanism on the weight itself said rewinding mechanism forms part of the weight and does not interfere with the proper operation of the clock as there is always a continuous pull on the section 4' of chain 4 even though the weight 5 is moving upwardly.

What I claim is:

1. In an automatic rewinding device for clocks, a weight provided with means for connecting the same with the power chain of the clock, a driving mechanism engaging said chain so as to cause the weight to move upwardly over the chain, a motor for operating said driving mechanism, a source of current, and means for directing said source of current to said motor, said means including a switching mechanism, said switching mechanism being provided with moving members for shifting the switch arm from an open to a closed position or vice versa, and stationary stops adjacent the extreme movements of the weight for causing the actuation of said switching mechanism, whereby current from said source of current will be turned on when the motor is in its lowest position and turned off when the motor is in its highest position.
2. In a rewinding device for clocks, a weight, and means for restoring the weight to its raised or wound position, said means including a driving motor, means for connecting the motor to the chain or cable supporting the weight, a source of current for the motor, an upper and lower stationary stop and means for controlling the passage of the current to the motor, said means including a switch on the weight and two sets of operating mechanism therefor mounted on the weight, one set being set in motion by the upper stop when the same is moved to its highest position and the other set moved by the lower stop when the weight has moved to its lowest position, said switch being adapted to switch on the current when the weight is in its lowest position and switch off the current when the weight is in its highest position.
3. In an automatic rewinding device of the character described, a weight adapted to be connected with a chain or cable, means arranged on the weight engaging the cable in such a manner as to raise the weight without moving the chain or cable when the means is rotated, a motor for rotating said means, means for supplying current to

said motor, a switch interposed in the circuit of said last mentioned means, oppositely moving mechanisms on the weight for opening and closing said switch, a stationary stop adjacent the top of said chain or cable for causing the actuation of one of the operating mechanisms, and a stationary stop adjacent the bottom of said chain or cable for causing the actuation of the other of said switch operating mechanisms, said switch being arranged to be opened when the weight is in its highest position and closed when the weight is in its lowest position so that said motor will act only in raising the weight.

4. In an automatic rewinding device of the character described, a weight adapted to be connected with the chain or cable of a clock, means arranged on the weight for causing the weight to travel over the chain or cable to the highest position assumed by the weight, said means including an electric motor, means for supplying current to said electric motor, a switch for turning on the current to said motor when the weight is in its lowest position and turning the current from said motor when the weight is in its highest position, means for moving said switch to a closed position, said means including a fixed stationary stop, a sliding plate, a catch engaging said sliding plate and holding the same in a predetermined position, a spring for urging said plate to a different position, a swinging arm provided with a projection mounted on said plate, means for guiding said arm so that the projection will strike said switch and move the same to a closed position, and means for moving said switch to an open position, said means comprising a fixed stop adjacent the upper end of said cable or chain, a sliding plate arranged on the weight, a catch for holding said plate against movement, means for giving the plate a tendency to move away from said catch, a swinging arm provided with a projection, said swinging arm being arranged on said plate, and means for guiding the swinging arm and projection so as to strike part of said switch and move the switch to an open position when said catch releases said sliding plate.

5. In an automatic rewinding device for clocks, a weight adapted to be connected to the cable or chain of a clock, means on the weight over which said cable or chain is adapted to be looped, said means including a rotatable power member, a gearing connected with said power member for rotating the same, an electric motor for operating said gearing, means including a switch for supplying said motor with current, said switch having operating arms projecting therefrom, means for operating one of said arms for closing said switch, said means

comprising a sliding plate, a spring for causing said plate to move in a given direction, said plate having a notch arranged therein, a swinging arm mounted in said

- 5 notch, said arm being provided with a projection, a guiding member for guiding said swinging arm and said projection so that the projection will strike one of the extending arms of said switch when the plate is
- 10 moved under the action of said spring, whereby said switch is closed, said guiding means moving said projection and said arm away from the switch when the sliding plate is moved against the action of said spring,
- 15 a catch for holding said plate in a given position when moved against the action of said spring, means on said plate for releasing said catch when the weight reaches its lowest position, and means set in motion by
- 20 said weight when the same reaches the highest position for turning said switch to an open position.

6. In an automatic rewinding device for clocks, a weight adapted to be connected with the cable or chain of a clock, power means on the weight for causing the weight to climb said cable or chain, said power means including an electric motor, means for supplying current to said electric motor, said means including a source of current and a switch, a member set in motion by the weight when the same reaches its lowest position for moving said switch to a closed position, a second member arranged

- 35 to open said switch when the weight reaches its highest position, said second member being set in motion by said weight, and means actuated by the weight for setting

both of said members as the weight moves upwardly.

7. In an automatic rewinding device of the character described, a weight adapted to be connected with the chain or cable of a clock, power means arranged on the weight for causing the weight to climb the chain or cable, said power means including an electric motor, means for supplying current to said electric motor, said means including a source of current and a switch, a set of mechanism set in motion by said weight when the same is moved to its lowest position for turning said switch to a closed position, a second set of mechanism set in motion by said weight when the same reaches its extreme upper position for opening said switch, and means operated by said weight during its upward travel for setting said first and second mechanisms, said last mentioned means comprising a pivotal member having arms or sections engaging said mechanisms, a link for moving said arms whereby said mechanisms are moved to a set position, a pawl adapted to be engaged by said weight, said pawl being connected to said link whereby as the weight is raised the link will be moved, and means for throwing said pawl out of engagement with said weight when both of said mechanisms have been set.

In testimony whereof I have signed my name to this specification in the presence of two subscribing witnesses.

CARL AUER.
